UNITED STATES PATENT OFFICE.

HARRY S. MORK, OF BROOKLINE, MASSACHUSETTS, ASSIGNOR TO AMERICAN LA FRANCE FIRE ENGINE COMPANY, INC., OF ELMIRA, NEW YORK, A CORPORATION OF NEW YORK.

FIRE-EXTINGUISHING COMPOSITION.

1,246,642.

Specification of Letters Patent.

Patented Nov. 13, 1917.

No Drawing.

Application filed March 27, 1917. Serial No. 157,642.

To all whom it may concern:

Be it known that I, HARRY S. MORK, a citizen of the United States, and resident of Brookline, county of Norfolk, State of Massachusetts, have invented a certain new and useful Fire-Extinguishing Composition, of which the following is a specification.

My invention relates in general to fire extinguishing compounds or compositions of the type embodying substances for the production of a relatively heavy blanket of gas or vapor to smother the fire, while at the same time possessing in its normal state, a permanence and so-called non-freezing character. Carbon-tetrachlorid has already been proposed and employed as a principal component of such compositions, and other substances have been added to the carbon-tetrachlorid to lower its freezing point, to retard the dispersion of the gas or vapor which is produced when the composition is employed for extinguishing the fire, and to reduce the corrosive action of the liquid on the metal of the container in which it is stored for use.

25 The fire extinguishing composition, according to my invention, comprises carbon-tetrachlorid as its main ingredient, and one or more ingredients for reducing the freezing point of the mixture, lowering the boiling point and retarding the rate of evaporation.

In my prior application filed February 26, 1917, serially numbered 151,099, I have set forth a fire extinguishing composition in

35 which carbon-tetrachlorid, chloroform and an aromatic ester, or a mixture of aromatic esters of relatively high boiling point are employed. Instead of using aromatic esters in the present instance, I employ pine oil.

40 In its broader aspect, the composition is not limited to the use of chloroform, but may comprise as its essential ingredients, carbon-tetrachlorid and pine oil, but I prefer the mixture of carbon-tetrachlorid, pine oil and chloroform, and regard this as constituting an important specific embodiment of a broader invention. Furthermore, where another freezing point lowering constituent in addition to pine oil is desired, I may use instead of chloroform, some other suitable ingredient such as for example, dichlormethane, or trichlorethylene; or mixtures of two or more may be employed with the pine oil.

Pine oil is an organic compound of cyclic

structure belonging to the class of terpenes. It is of relatively high boiling point and moderately high evaporation rate. Added to carbon tetrachlorid, it serves to lower the boiling point and to retard the evaporation, while at the same time exhibiting a marked depressing effect upon the freezing point. The pine oil is, however, combustible and for this reason it is important that the percentage of pine oil should not be too high, as otherwise the fire extinguishing properties of the composition would suffer. Where it is desired that the composition should possess the low freezing point which is customarily required, as for example -50° F. or lower, it becomes important to include chloroform with the carbon-tetrachlorid and pine oil, as in this way the desired low freezing point is attained without increasing the percentage of pine oil unduly. At the same time, the use of pine oil may be regarded as serving also to economize chloroform.

In order to illustrate the low freezing point obtained by the mixture of carbon-tetrachlorid and pine oil, I may state that a mixture of, for example 95% of carbon-tetrachlorid and 5% of pine oil by volume, exhibits a freezing point of somewhere in the neighborhood of -28° F. while with 90% carbon-tetrachlorid and 10% pine oil, the freezing point becomes still lower, being close to -45° F. Such mixtures constitute efficient fire extinguishing compositions and are suitable for use where the lower freezing points are not demanded.

The effect of including chloroform in the composition will be at once apparent from a specific example of the invention, in which the three essential ingredients are employed. I may refer to a composition comprising 90% carbon-tetrachlorid, 5% pine oil and 5% chloroform, by volume. The freezing point of such a mixture is in the neighborhood of -52° F. and thus comes within the usual requirements with respect to the ability to resist low temperatures while remaining in the liquid state. It will be apparent that corresponding changes in freezing point will be obtained by varying the proportions of the several ingredients, and the invention is not to be understood as limited precisely to any one or more of the specific examples recited.

The compositions which I have so far

tested, embodying the ingredients of the present invention, are found to exhibit good fire extinguishing properties, and in addition to the low freezing points already mentioned, they offer the advantages of being permanent liquids under all ordinary conditions of storage in the containers usually employed, not showing any marked corrosive action upon the material of such containers, and being free from sediment or deposits during long periods of non-use.

I claim:

1. A fire extinguishing composition con-

taining as essential ingredients, carbon-tetrachlorid and pine-oil.

15

2. A fire extinguishing composition comprising as essential ingredients, carbon-tetrachlorid, pine oil and another freezing point lowering constituent.

3. A fire extinguishing composition comprising as essential ingredients, carbon-tetrachlorid, pine oil and chloroform.

4. A fire extinguishing composition comprising approximately 90% of carbon-tetrachlorid, 5% chloroform and 5% pine oil.

HARRY S. MORK.
